(57) CLAIM

The ornamental design for a desk, as shown and described.

DESCRIPTION

FIG. 1 is a front, top and left perspective view of a desk showing our new design;

FIG. 2 is a front, top and right perspective view thereof;

FIG. 3 is a rear, top and left perspective view thereof;

FIG. 4 is a front view thereof;

FIG. 5 is a rear view thereof;

FIG. 6 is a left side view thereof, a right side view being a mirror image of the left side view; and,

FIG. 7 is a top view thereof.

The broken lines depict portions of the desk that form no part of the claimed design.

1 Claim, 7 Drawing Sheets
